INVENTOR
ALPHONSUS M. CRUNICAN.

My testimony for app.

UNITED STATES PATENT OFFICE.

ALPHONSUS MICHAEL CRUNICAN, OF LONDON, ONTARIO, CANADA.

CUSHIONING-SPRING SUPPORT FOR VEHICLES.

1,357,959.

Specification of Letters Patent. Patented Nov. 9, 1920.

Application filed July 24, 1919. Serial No. 312,952.

To all whom it may concern:

Be it known that I, ALPHONSUS MICHAEL CRUNICAN, a subject of the King of Great Britain, and resident of the city of London, 5 in the county of Middlesex, in the Province of Ontario, Canada, have invented certain new and useful Improvements in Cushioning-Spring Supports for Vehicles, of which the following is a specification.

10 The object of the invention is to devise a simple construction of resilient support, which may be utilized for cushioning various parts of a vehicle such as the seat and the like, in such a way that the shock received is 15 distributed evenly so that it is equalized and the supported member carried evenly when under shock producing an even yield and preventing any teetering of the carried member as the shock is absorbed, and it 20 consists essentially of the arrangement and construction of parts as hereinafter more particularly explained.

Figure 1 is a side elevation of my device showing it interposed between a carrying 25 member and a member to be supported thereby.

Fig. 2 is a plan view of my resilient support.

Fig. 3 is a plan view of a modified construction.

In the drawings like characters of reference indicate corresponding parts in the various figures.

1 indicates the supporting member and 2 a 35 member adapted to be carried by my resilient support 3 and 4 indicate lever arms set crosswise one of the other and connected together intermediately of their length by a pivot pin 5, the members 3 and 4 being 40 spaced apart as indicated in Fig. 2. 6 indicates a pin extending inwardly from the lower portion of the member 4. 7 indicates a pin extending inward from the lower portion of the member 3. 8 indicates a bowed 45 spring which is carried at its ends by the pins 6 and 7 and bows upwardly so as to form a bearing support for the pivot pin 5.

The extreme ends of the members 3 and 4 50 may be suitably connected to the carrying member 1 and to the supported member 2 by means of projecting pins 9 operating in slotted brackets 10 or by any other suitable means desired.

It will thus be seen that when the vehicle 55 is subjected to jar the members 3 and 4

will tend to align themselves one with the other, carrying the pivot pin 5 downwardly and the pins 6 and 7 upwardly thereby producing a cushioning action which will take up the shock produced by the jar. 60

In Fig. 3, I have shown an alternative form in which two springs are utilized. In this form 11 and 12 are the cross members pivotally connected together by a pin 13, which projects laterally from each side of 65 the cross members. 14 indicates a pin, which is secured in the lower portion of the member 11 and 15 indicates a pin which is secured in the lower portion of the member 12. 16 indicates a bowed spring secured to 70 one end of each of the pins 14 and 15, being bowed upwardly so as to resiliently carry the correspondingly projecting end of the pivot pin 13. The opposite ends of the pins 14 and 15 projecting from the opposite side 75 of the cross members carry a bow spring 17 which is bowed upwardly so as to carry the opposite end of the projecting pivot pin 13.

From this description it will be seen that I have devised a very simple form of cushioning means whereby the various parts of a vehicle may be resiliently carried so as to take up the jar evenly and which acts as a shock absorber distributing the shock equally 80 so that the carried member is held level during the absorption of the shock. 85

What I claim as my invention is.

1. A cushioning spring support for vehicles comprising a pair of crossed bar members, a pivot pin connecting the bar members 90 together intermediately of their length, and a bowed spring carried by the lower portions of the crossed members and extending upwardly to form a bearing support for the pivot pin. 95

2. A cushioning spring support for vehicles comprising a pair of crossed bar members spaced apart, a pivot pin connecting the bar members together intermediately of their length, pins extending inwardly from the lower portions of the bar members at each side of the pivot pin, and a bowed spring carried at its ends by the inwardly projecting pins and extending upwardly to form a bearing support for the pivot pin between 100 the crossed bar members. 105

3. A cushioning spring support for vehicles comprising a pair of crossed members pivotally connected together intermediately of their length and disposed in spaced re- 110

lation, a bowed spring arranged between the members with the intermediate bowed portion of the spring engaging the under side of the pivot and the ends of the spring secured to the crossed members on opposite sides of the pivot and below the same.

4. A cushioning spring support for ve-

hicles comprising a pair of crossed members pivotally connected together intermediate of their length and resilient means attached to the lower ends of said members providing a cushioning support engaging the under side of the pivot connecting the members.

ALPHONSIUS MICHAEL CRUNICAN.
